TOWEL BAR BRACKET

John F. Bonistall, 525 Military Road, Zanesville, Ohio.

Filed May 15, 1958, Ser. No. 50,910

Term of patent 14 years

(Cl. D4—3)

Fig. 1 is a front perspective view taken from the right side of a towel bar bracket embodying my new design; Fig. 2 is a rear perspective view taken from the left side thereof; Fig. 3 is a right side elevational view thereof; and Fig. 4 is a horizontal cross-sectional view thereof taken on line 4—4 of Fig. 3.

I claim:

The ornamental design for a towel bar bracket, as shown.
